UNITED STATES PATENT OFFICE.

ADOLPH WUNDER, OF NEW HAVEN, CONNECTICUT, ASSIGNOR TO
SARGENT & CO., OF SAME PLACE.

DESIGN FOR DRAWER-PULL.

Specification forming part of Design No. **6,162**, dated October 1, 1872.

To all to whom it may concern:

Be it known that I, ADOLPH WUNDER, of New Haven, in the county of New Haven and State of Connecticut, have invented a new Design for Drawer-Pull; and I do hereby declare the following, when taken in connection with the accompanying drawing and the letters of reference marked thereon, to be a full, clear, and exact description of the same, and which said drawing constitutes part of this specification, and represents in—

Figure 1 a front view, and in Fig. 2 a top view.

This invention relates to a design for that class of drawer-pulls which are formed from cast metal, in a box or shell form; and it consists in the peculiar configuration and ornamentation, as shown in the accompanying illustrations, and as hereinafter described.

The lower edge of the pull is straight, the two ends running back therefrom inclined outward, the top turning at right angles from the ends a short distance inward, and from these ends in a segmental form, the top inclining outward, as seen in Fig. 1. The front and top are ornamented, as shown, by tracery in relief upon a matted or other surface.

To secure the pull to the drawer-front, ears are provided at each end; but these form no part of the design.

I claim as my invention—

The design for drawer-pull, as herein described, and as shown in the accompanying illustrations.

ADOLPH WUNDER.
